UNITED STATES PATENT OFFICE.

HENRY REBSAMEN AND AUGUST KIEFFER, OF CHICAGO, ILLINOIS.

WORT-COOLER.

No. 799,869.

Specification of Letters Patent.

Patented Sept. 19, 1905.

Application filed March 6, 1905. Serial No. 248,453.

To all whom it may concern:

Be it known that we, HENRY REBSAMEN and AUGUST KIEFFER, citizens of the United States, residing at Chicago, in the county of 5 Cook and State of Illinois, have invented a new and useful Improvement in Wort-Coolers, of which the following is a specification.

Our invention relates to an improved construction of cooler of the variety employed in 10 the art of brewing beer for cooling the wort that is taken from the fermenting-room to the stock or chip cellar and involving the generally-stated construction of one or more vertical series of horizontal parallel pipes connect- 15 ed from one to the other at their ends by elbows or "return-bends" to form a coil, with connecting means between the outlet end of one series to the inlet end of another to render the course of the wort continuous in its 20 back-and-forth travel through the cooler. The refrigerating medium employed in this variety of cooler for exerting the cooling influence upon the coursing wort is anhydrous ammonia or other similarly-acting agent, oper- 25 erating either directly on the cooler-pipes or indirectly thereon through the medium of brine in which the cooler is immersed.

Our improved device belongs to the kind of these coolers in connection with which 30 brine is the immediate cooling medium employed; and our primary object is to afford ready access to any pipe in a coil for cleaning it or other purpose when the cooler is immersed in a brine-tank with which it is per- 35 manently associated.

Our invention consists in the general and more specific construction of parts whereby the aforesaid object and further objects are accomplished.

40 Referring to the accompanying drawings, Figure 1 is a plan view of our improved apparatus. Fig. 2 is a section taken at the line 2 on Fig. 1 and viewed in the direction of the arrow. Fig. 3 is an end view of the appa- 45 ratus. Fig. 4 is a section taken at the line 4 on Fig. 1 and Fig. 2 and viewed in the direc- 50 tion of the arrow. Fig. 5 is an enlarged view, in broken sectional elevation, of one of the elbow-coupling devices with its connections; Fig. 6, a broken-away section taken at the 55 line 6 on Fig. 5 and viewed in the direction of the arrow; Fig. 7, an end elevation of the coupling device; Fig. 8, a section taken at the line 8 on Fig. 5 and viewed in the direc-

view of the yoke with its attachments re- moved, showing the elbow in section.

A is a tank, shown in its preferred rectangular form, resting on suitable supports *a*. 60

B are wort-conduit pipes extending through opposite end walls of the tank, three vertical rows or series of the pipes being represented, each series comprising eight parallel pipes, though the number of the series 65 and of the pipes may vary from the representation thereof. In each series the lowermost pipe is connected from one end with the adjacent end of the next pipe by a U-shaped or return-bend coupling or elbow, the oppo- 70 site end of the last-named pipe being similarly connected with the adjacent end of the pipe next above it, and so on throughout each series to form it into a pipe-coil.

Our invention lies in the combination with 75 a brine-tank of a wort-cooling coil and also in the general as well as the more specific construction of and combination with the pipes of the coupling devices to adapt them to be readily disconnected for affording access to 80 the pipes at their ends, and as the couplings all involve the same construction description of one of them will suffice.

Each pipe B passes at its ends through open- 85 ings in the tank-walls in which they find end bearings, and the pipe is rigidly fastened in place at each end by threading it, as represented in Fig. 5, encircling it against the inner side of the tank-wall with an internally-threaded split collar *b*, fastened by bolts *b'* to 90 clamp it on the pipe, and applying to the projecting pipe end a jam-nut *c* to bear against the outer surface of the wall. Thus the pipes are rigidly fixed in the tank with their threaded ends projecting beyond the walls in which 95 they find bearings, and they are supported at intervals between their ends by pairs of parallel vertical bars *d d*, rising from the base of the tank, the members of each pair being fastened together by bolts *e* at intervals and 100 spaced apart to permit the pipes to pass be- 105 tween them, the bolts affording bearings for the pipes. Coils C for the primary refrigerating medium, as anhydrous ammonia, are also supported in desired number in the tank 105 by resting on bolts *e'*, which connect the spaced members of pairs of vertical bars *d'*, rising at intervals from the bottom of the tank and between which members the coils pass from headers *C* and *C'* at their upper and 110 lower ends, respectively, the lower header communicating with the suction side and the

upper one with the discharge side of any ordinary or suitable gas-compressor. (Not shown.)

D represents as a whole the coupling device 5 for pipes B, comprising the following described construction: A tubular elbow f, preferably of the U shape represented, has formed upon it to extend on opposite sides thereof across its transverse center flanged guide-bearings f', f', and the elbow is provided near each end with a flange f² and outer and inner shoulders f³ and f⁴, Fig. 5. A strap-bar g, having a central opening g', terminates at its ends in annular heads g², which encircle ends 10 of pipes B to be coupled, and in each head there fits a thimble h, screwed upon the headed end of a pipe and having seated in its expanded outer end a gasket-packing h'. The elbow f is straddled by a yoke i, formed in two similar longitudinal sections provided with bolting-flanges i' near their opposite ends, at which they are secured together by bolts i² to embrace the guide-bearings f'. A bolt k passes through a longitudinal opening k', formed in one end of the yoke, wherein it is confined against withdrawal at its head, Fig. 6, and the threaded end of this bolt passes through the central opening g' in the strap-bar and is fastened by a nut k². A threaded 20 stem l, provided with a handle l' on its outer end and a head l² on its inner end, works in a threaded opening in the outer end of the yoke and is confined at its head in a T-shaped slot l⁴, formed in the outer end of the guide-bearings f'. 25

By the described construction of the coupling device D to loosen an elbow f the stem l is turned in one direction at its handle l' to cause the head l² by engagement with the recess 40 l⁴ to withdraw the elbow from its seats at h', when the elbow may be freely turned on the bolt-bearings of the yoke i to extend at a right angle or other angle to its fastened position illustrated, and thus clear the ends of 45 the respective pipes B to render them accessible for cleaning and other purposes. To readjust an elbow, its ends are brought coincident with the seating-gaskets h', when the stem l is turned in the proper direction to 50 force its head l² inward, and thus press and clamp the elbow against its seats. The yoke, pivotally supported on the bearing afforded by the strap-bar, with the operating-screw l working in its outer end against the elbow, 55 forms a rotatable holder for the elbow, in which it has a limited longitudinal movement for tightening it against and freeing it from the pipe ends and with which it is adapted to be turned or rotated when so freed for taking it out of the way and permitting access 60 to be had to the pipe ends.

The lowermost and uppermost pipes B in each coil extend at one end farther beyond an end wall of the tank than the intermediate 65 coupled pipes, and two of these extensions of

the uppermost pipes are equipped with shut-off valves at m m. The extended lower pipes discharge into a header n, provided between its connections with the extensions with shut-off valves n'. The lowermost pipe in the first 70 coil is connected from its extension at a point behind the header n with the extension of the uppermost pipe of the intermediate coil by a pipe B', and the lowermost pipe in the intermediate coil is connected from its extension 75 with the extension of the uppermost pipe of the third or last coil by a pipe B².

With the tank A supplied with brine cooled by the action of the coils C the wort to be cooled is run into the uppermost pipe of the first 80 coil at t, flows downward through that coil and upward through the connecting-pipe B' into the upper end of the intermediate coil, through which it courses downward and from the lower end of which it passes through the 85 connecting-pipe B² into the upper end of the third coil, coursing downward through the latter and discharging from the header n at o. When it is desired to use only the first coil for cooling, the valves m m may be closed, 90 causing the wort after coursing downward through that coil to flow immediately through the header n to the discharge o, both valves n' being then open. If it be desired to use only the first and second coils, the valve n' 95 nearest the discharge o is opened and the other valve n' is closed and the valve m at the upper end of the pipe B² is closed to shut off the end coil.

What we claim as new, and desire to secure 100 by Letters Patent, is—

1. In a beer-cooler of the character described, the combination of a brine-tank, a plurality of series of pipes passing at their ends through opposite walls of the tank, the 105 pipes in each series being coupled beyond said walls to form them into a coil, a valve-equipped header into which an end pipe of each series discharges, an inclined valve-equipped pipe connecting the discharge end 110 of one coil with the inlet end of another coil beyond an end of said tank, and means for cooling the brine in said tank.

2. In a beer-cooler of the character described, a pipe-coil for the wort to be cooled, 115 comprising, in combination, a series of pipes and a coupling device for adjacent ends of the members of each pair of pipes in the series, consisting of an elbow meeting the two pipe ends to be coupled, a strap-bar connecting the members near said ends, a yoke embracing said elbow transversely and rotatably connected at its inner end with said bar, and a threaded stem rotatably engaging with 120 said elbow and working in the outer end of said yoke, for the purpose set forth.

3. In a beer-cooler of the character described, a pipe-coil for the wort to be cooled, 130 comprising, in combination, a series of pipes and a coupling device for adjacent ends of the

members of each pair of pipes in the series, consisting of an elbow seating against the two pipe ends to be coupled, a strap-bar connecting the members near said ends, transverse 5 guide-bearings on the elbow, a yoke embracing the elbow at said bearings, a pivotal bolt connection between said strap-bar and one end of said yoke, and a handle-equipped screw-stem working in the opposite end of 10 said yoke and engaging said guide-bearing, for the purpose set forth.

4. In a beer-cooler of the character described, the combination of a brine-tank, a series of pipes passing at their ends through 15 and projecting beyond opposite walls of the tank, means for cooling the brine in said tank, and a coupling device for adjacent ends

of the members of each pair of pipes in the series, consisting of a bearing between said members, an elbow seating against the two 20 pipe ends to be coupled, and a screw-operated holder carrying said elbow, supported to rotate axially on said bearing and adapted to press the elbow in seating it against the pipe ends by turning the screw in one direction 25 and to cause withdrawal of the elbow from its seat by turning said screw in the opposite direction.

HENRY REBSAMEN.
AUGUST KIEFFER.
